UNITED STATES PATENT OFFICE.

MAX HENDLER, OF STAUNTON, ILLINOIS.

CLOCK-SYNCHRONIZER.

1,103,581.

Specification of Letters Patent.

Patented July 14, 1914.

Application filed October 23, 1913. Serial No. 796,864.

To all whom it may concern:

Be it known that I, MAX HENDLER, a subject of the Czar of Russia, residing at the city of Staunton, State of Illinois, have invented a certain new and useful Improvement in Clock-Synchronizers, of which the following is a full, clear, and exact description, such as will enable others skilled in the art to which it appertains to make and use 10 the same, reference being had to the accompanying drawings, forming part of this specification, in which the illustration is a perspective view showing my invention and its application to the clock-casing.

15 The object of my invention is to provide a simple and easily operated mechanism for synchronizing the striking mechanism of clocks with the time indicating mechanism.

As is well known, it frequently occurs that 20 clocks are allowed to run down and are reset by inexperienced persons before they are wound. It sometimes occurs also that the striking mechanism is not wound and runs down before the time mechanism does.

25 These occurrences will cause the relation of the striking mechanism and the time indicating mechanism to be altered so that the clock will not strike the time indicated on the dial. Persons unfamiliar with the clock

30 mechanism are at a loss to remedy this state of affairs and either allow the clock to go on striking out of time or in seeking to correct it, put the clock out of order. By means of the mechanism illustrated in the drawing,

35 the inexpert person is enabled to synchronize the striking mechanism with the time mechanism by simply pressing a button in the casing of the clock and the addition of this feature renders the clock more desirable

40 in the eyes of the ordinary purchaser, and, therefore, renders it more salable. By means of the form of device employed, I am enabled to position the operating element

45 near the base of the clock casing where it may be easily reached and yet is inconspicuous.

As illustrated in the drawings, 1 is the clock casing, and 2 a portion of the frame. Let 4 represent the striking wheel and 5 the 50 striking wheel escapement detent. The counting wheel is indicated at 6 and the counting detent at 7. These are all well known portions of a clock striking mechanism and operate in the usual fashion, the 55 detents 5 and 7 being both fixedly mounted on the shaft 8 and operating to control the

rotation of the striking wheel 4. As is usual in clock striking mechanisms, the counting wheel 6 is provided with peripheral notches 6^a which are divided into groups by the 60 measuring notches 6^b. When the controlling detent 7 drops into one of the measuring notches 6^b the detent 5 will be permitted to engage suitable means on the striking wheel 4 to prevent further rotation thereof 65 and further striking. When the detent 7 is lifted out of one of the measuring notches 6^b the striking and counting wheels are released to rotate, the detent 7 engaging successively the peripheral notches 6^a, and during 70 this rotation, the striking of the clock continues. As a means for thus lifting the detents 7 so as to free the striking mechanism and permit it to assume the proper position relative to the time indicating 75 mechanism, I provide the lifting link 9 which is slidably supported on a portion of the clock frame 2. This lifting link has an ear 9^a which projects under the detent 7 in position to engage the same and lift it out 80 of any of the measuring notches 6^b when the lifting link 9 is raised. A suitable spring 10 retains lifting link 9 normally in lowered position where it does not interfere with the operation of the detent 7. Mounted 85 in the clock casing is a push button 11 which may be moved inwardly against the influence of the extension spring 12. Push button 11 carries a cam 14 which engages the lifting link 9 in such fashion that when 90 the button 11 is pushed inwardly, the cam 14 raises the lifting link 9 so that it will engage the detent 7 to release the striking mechanism. The button 11 is seated in a proper seat 15 supported in the casing at a 95 point preferably near the base of the clock where the button may be easily reached when the clock is positioned on a high support.

The operation of the device will be obvious from the foregoing description, from which it will be apparent that this device provides a simple and easily operated attachment for synchronizing the striking mechanism of a clock with the time indicating mechanism.

What I claim is:

1. In a clock including a striking mechanism and controlling detents therefor, a means for operating the detents comprising 110 in combination a vertically movable lifting link co-operating at its upper end with said

detents, a cam member coöperating with said lifting link at its lower end, and a push button disposed in the lower portion of the clock casing and adapted to operate said cam member for the purpose described.

2. In a clock having a striking mechanism including controlling detents, a means for operating said detents comprising a lifting link slidably mounted upon a portion of the 10 clock frame, said lifting link being provided at its upper end with an extension adapted to coöperate with said detents, said lifting link being provided at its lower extremity with a lateral extension, a cam member

adapted to coöperate with said lateral extension to slide the link upwardly, and means mounted in the lower portion of the clock casing and operable from the exterior thereof for operating said cam member to lift said link.

20 In testimony whereof I hereunto affix my signature in the presence of two witnesses, this 21st day of July, 1913.

MAX HENDLER.
